UNITED STATES PATENT OFFICE.

JOSEPH WARD, OF EAST HUNTINGTON, WEST VIRGINIA.

RAIL-JOINT.

1,323,617.

Specification of Letters Patent.

Patented Dec. 2, 1919.

Application filed May 16, 1919. Serial No. 297,507.

To all whom it may concern:

Be it known that I, JOSEPH WARD, a citizen of the United States, residing at East Huntington, in the county of Cabell and 5 State of West Virginia, have invented certain new and useful Improvements in Rail-Joints; and I do hereby declare the following to be a full, clear, and exact description of the invention, such as will enable others 10 skilled in the art to which it appertains to make and use the same.

The present invention relates to rail joints, and aims to provide the meeting ends of the rail sections with novel and improved, 15 yet simple and effective means arranged to interfit so as to hold the rail sections in alinement and prevent transverse displacement thereof relatively to one another, thereby maintaining the rail sections in 20 alinement without the necessity for using fish plates or the like.

With the foregoing and other objects in view, which will be apparent as the description proceeds, the invention resides in the 25 construction and arrangement of parts hereinafter described and claimed, it being understood that changes can be made within the scope of what is claimed without departing from the spirit of the invention.

30 The invention is illustrated in the accompanying drawings, wherein—

Figure 1 is a side elevation of one form of joint, a portion being broken away.

Fig. 2 is an end view of one rail section.

35 Fig. 3 is a plan view showing the rail sections separated.

Fig. 4 is a side elevation of another form of joint, portions being broken away.

40 Fig. 5 is a plan view of the joint shown in Fig. 4 with the rail sections separated.

Fig. 6 is a view similar to Fig. 4 illustrating a further modification.

Fig. 7 is a side elevation of a still further modified form of joint, portion being broken 45 away.

Fig. 8 is a plan view of the joint shown in Fig. 7, with the rail sections separated.

Fig. 9 is a side elevation of the further variation including a short rail section between the main rail sections, portions being broken away.

Fig. 10 is a plan view of the joint shown in Fig. 9, portions being broken away and shown in section.

55 Referring to Figs. 1, 2 and 3, the rail sections are designated 1, and 2, and they are

of usual cross section, being provided with the respective bases 3 and 6, webs 4 and 7, and heads 5 and 8. The bases, webs and heads of the two rail sections are in abutment and are formed to interfit in a manner to prevent relative transverse displacement. Thus, the ends of the base 6, web 7 and head 8 of the rail section 2 are flush in a vertical plane, while the end of the web 4 of the rail section 1 terminates short of the base 3 and head 5 of said rail section, providing for the engagement of portions of the base 6 and head 8 in the base 3 and head 5 with the webs 4 and 7 abutting at a point offset longitudinally from the point where the bases and heads of the rail sections abut. The end portion of the head 8 is reduced in width, being cut away at both sides, to provide a tapered tongue 9 above the web 7, and the opposite flanges or side portions of the base are cut away, leaving the end portion of the base 6 of reduced width and of dovetail shape, as at 10, said portion 10 being at the lower edge 80 of the web 7. The web 4 is cut away from between the ends of the base 3 and head 5, and the head 5 has a tapered longitudinal recess 11 extending from the end thereof with its inner or closed end flush with or in 85 the vertical plane of the end of the web 4. The base 3 is provided with a dovetailed recess 12 extending from the end thereof longitudinally to a point coextensive with the recess 11, the inner or closed end of the 90 recess 12 also being flush with or in the vertical plane of the end of the web 4. The recesses 11 and 12 are of a size to snugly receive the tongues or portions 9 and 10. Thus, by raising the base 6 slightly higher 95 than the base 3 and moving the rail sections longitudinally against one another into abutment, the web 7 and tongue 9 can move into the recess 11 with the tongue 10 above the recess 12. Then, by letting the rail section 2 move downwardly, the tongue 9 will come to rest snugly in the recess 11, while the tongue 10 will interlock within the recess 12, with the ends of the base 3 and head 5 abutting the shoulders at the ends of the base 6 and head 8 at a point offset longitudinally from the point where the webs 4 and 7 abut. The rail sections are thus engaged to hold them in alinement and prevent relative transverse displacement of the 105 meeting ends, and the tongue 10 and recess 12 will also prevent the separation of the 110

rail sections beyond a slight limited amount to permit of contraction of the metal. The ends of the rail sections are readily formed as described and illustrated, by cutting out 5 the side portions of the rail section 2 from top to bottom at the end thereof, and cutting out the end portion of the web 4 and the recesses in the ends of the base 3 and head 5 from top to bottom. The cutting 10 away of the web 4 provides for the convenient cutting of the recesses 11 and 12.

Referring to Figs. 4 and 5, wherein a second form of the invention is depicted, the tongues or reduced portions 9^a and 10^a of 15 the head 8 and base 6 are of the same width or thickness as the web 7 and are flush with the sides of the web, but project slightly beyond the end of the web which is cut away, as well as the end of the web 4, so that the 20 two webs abut between the abutting portions of the bases and heads. The recesses 11^a and 12^a in the head 5 and base 3 are likewise of the width or thickness of the web 4 and extend longitudinally beyond the end of 25 the web. These rail sections can be moved together longitudinally into abutment, and will be held in alinement, the tongues in fitting in the recesses preventing relative transverse displacement of the rail sections, and 30 the tongues in extending above and below the end of the web 4 also preventing vertical displacement between the rail sections.

Fig. 6 shows the end of the web 7 flush with the ends of the tongues 9^b and 10^b, and 35 the end of the web 4 flush with the closed ends of the recesses 11^b and 12^b, and the end of the web 7 is provided with an extension 13 fitting within a recess 14 provided in the end portion of the web 4, thereby preventing relative vertical displacement of the 40 rail sections.

As shown in Figs. 7 and 8, the tongues 9^c and 10^c are both of dove-tailed form, and the recesses 11^c and 12^c are of similar shape, 45 like the tongue 10 and recess 12 shown in Figs. 1, 2 and 3.

In Figs. 9 and 10, a short rail section 1^d is

disposed between the rail sections 2, and has the base 3^d, the web 4^d of the section 1^d being of the same width as the head 5^d. The 50 ends of the webs 7 are flush with the end of the heads 8, while the opposite flanges or side portions of the bases 6 of the rail sections 2 are cut away to provide the tongues 10^d of the same width or thickness as the 55 webs 7 and flush with the sides thereof. The ends of the heads 5^d are cut away to abut the ends of the heads 8 with the web 4^d extending under the heads 8 and overlapping the opposite sides of the webs 7. 60 The ends of the webs 4^d and base 3^d have vertical recesses or slots 12^d receiving the ends of the webs 7 and the tongues 10^d.

Having thus described the invention, what is claimed as new is:—

1. Abutting rail sections each having a base, web and head, one rail section having the end portion of its web cut away and having recesses in the end portion of its base and head extending from top to bottom thereof, the other rail section having the side portions of the base and web cut away from top to bottom to provide tongues to enter said recesses.

2. Abutting rail sections each including 75 a base, web and head, one rail section having the end portion of its web cut away and recesses in the end portions of its base and head from top to bottom thereof of about the same width and in the vertical plane 80 of the web, the other rail section having the side portions of its base and head cut away from top to bottom to provide tongues at the upper and lower edges of the corresponding web of about the same width as the 85 web to enter said recesses.

In testimony whereof I have signed my name to this specification in the presence of two subscribing witnesses.

JOSEPH WARD.
